UNITED STATES PATENT OFFICE.

HOWARD J. WEBSTER, OF PHILADELPHIA, PENNSYLVANIA.

STEAM-BOILER.

1,225,293.

Specification of Letters Patent.

Patented May 8, 1917.

Application filed April 17, 1916. Serial No. 91,642.

To all whom it may concern:

Be it known that I, HOWARD J. WEBSTER, a citizen of the United States, residing at Philadelphia, in the county of Philadelphia 5 and State of Pennsylvania, have invented certain new and useful Improvements in Steam-Boilers, of which the following is a specification.

My invention relates to improvements in steam boilers and more especially of the horizontal return flue or tubular type in which the lower section of the boiler shell is disposed over the combustion chamber of the furnace and the hot gases after flowing 15 the length of the boiler in one direction and impinging against and radiating their heat against the underside of the boiler shell, pass through the longitudinal tubes or flues within the boiler in the opposite direction 20 and out to the stack.

The objects of my invention are: First, to construct a steam boiler of the type above indicated, in which the fire tubes or flues within the boiler are so arranged and 25 grouped, as to promote a positive circulation of water and efficient production of steam without priming within the boiler, and at the same time by virtue of such arrangement and grouping of tubes or flues, and 30 non-interference of the moving masses of water due to proper circulation of the water in the boiler, permit the generated steam globules to rise swiftly and pass in a direct path from the above indicated and properly 35 disposed fire tubes and be liberated at a maximum steam disengaging area with a minimum resistance throughout each transverse section of the entire length of the boiler. Second, to construct a steam boiler 40 in which the arrangement and grouping of the fire tubes are such in which all the functions and advantages above indicated are efficiently carried out, yet the boiler may be properly constructed and installed at a 45 minimum cost, and all the interior and exterior surfaces of the fire tubes be quickly inspected and cleaned. Third, other advantages of construction and operation of my invention will be apparent and be more 50 fully disclosed in the detailed description.

The invention consists of structural features and relative arrangements of parts which will be hereinafter more fully described and particularly pointed out in the 55 appended claims.

In the two sheets of drawings in which similar reference characters indicate the same parts in the several figures:

Figure 1, is a longitudinal sectional view of a boiler and furnace embodying the preferred arrangement of my invention; 60

Fig. 2, is an enlarged transverse sectional view of the boiler showing the arrangement of the groups of the fire tubes and the disposition of said tubes in the several groups; 65

Fig. 3, is a similar view as Fig. 2, showing a modified form of my invention with circulating funnels placed in position between the groups of fire tubes. 70

Referring to Fig. 1, 10 is the cylindrical boiler shell provided with the improved arrangement and grouping of fire tubes to be presently described. Said boiler shell 10 is properly supported on any common and well known form of side walls, by means of rods 11, engaging the opposite sides of the boiler shell 10 at their lower ends and having their upper ends carried by I-beams 12 supported by said side walls. Said boiler shell is incased by the usual furnace front 13, provided with the fuel opening 14, and ash pit opening 15. A back wall 16 is properly disposed with respect to the rear of the boiler shell in order to form the usual fire chamber 17 having an opening 18 leading to the exterior. Grate bars 19 are properly supported to receive the fuel thrown into the furnace chamber 20, and 21 is the ash pit. The furnace chamber 20 under the forward 75 end of the boiler shell 10 communicates with the rear fire chamber 17 by a combustion passageway 22 directly under the rear section of the lower side of the boiler shell 10 extending from the bridge wall 20' to the chamber 17, and said passageway 22 is semi-circular in cross-section and made to conform to the curvature of the shell by brick work 23 as indicated, in order to have the 80 heat of the furnace gases deflected and made to impinge against the underside of the boiler shell. The boiler shell 10 is provided with front tube sheet 24 and rear tube sheet 25, and smoke box 26' having an opening 27, which leads to a stack, not shown. All the 85 openings 14, 15 and 18 may be supplied with the usual form of doors common in boiler furnace constructions. The parts of the boiler and furnace described as above indicated are similar to the common and well 90

openings 14, 15 and 18 may be supplied with the usual form of doors common in boiler furnace constructions. The parts of the boiler and furnace described as above indicated are similar to the common and well 105 110

known types of boiler furnaces and form no part of the distinguishing features of my invention.

Within said boiler shell 10, and having their ends properly secured to the flue or tube sheets 24 and 25 are arranged a plurality of fire tubes 26, 26 (see Fig. 2), said tubes 26 are preferably arranged in three groups or banks, a central group or bank A and two side groups or banks B and C, and the central group or bank A being separated from the two side groups or banks B and C, by narrow passageways 28, 28, and each of the two side groups or banks B and C being also separated from the boiler shell by a passageway 29, each of said passageways 28 and 29 extending longitudinally the full length of the boiler and from the uppermost row of tubes to the lower section of the boiler shell 10.

The boiler tubes 26, 26 of each group or bank are arranged as shown in Figs. 2 and 3, in vertical rows with the horizontal rows staggered, and said tubes are made proportionately smaller and in greater number than tubes usually employed in boilers of the fire tube type, thereby providing a larger area of heating surface for the same diameter of boiler than heretofore employed.

The above arrangement of fire tubes forms uninterrupted and vertical circulation paths for the water and steam and at the same time vertical spaces between the tubes, whereby easy access may be had to examine the fire tubes and permit the inspection and cleaning of every part of the water surface of each tube.

Furthermore, by arranging the fire tubes in vertical rows with the horizontal rows staggered, the centers of the uppermost row of fire tubes will not be in the same horizontal plane, and hence the steam disengaging width between the sides of the uppermost row of fire tubes and boiler shell (as indicated in dotted lines in Fig. 2), is greatly in access of the old style of arrangement of fire tubes or lay out, and hence permits a quicker disengagement of the globules of steam and reduces priming to a minimum, and assures a maximum amount of dry steam under all conditions of work, which is a most essential feature in the efficient operation of a steam plant.

If desired circulating funnels 30, 30, may be placed at suitable intervals along and in the narrow passageways 28, 28 between the groups or banks A, B and C of fire tubes 26, 26, as shown in dotted lines in Fig. 1. Said funnels 30, are of such size and form as will enable them to be passed through the man holes 31 of the boiler as indicated in dotted lines in Fig. 3. The funnels 30 are enlarged at their upper ends so as to rest on and be supported by the upper fire tubes, and at the same time lead the upper water

into the funnels and are of such length as to extend down to the lower fire tubes as shown.

The operation of the invention is follows:

The boiler having been filled to the proper level and the fire started, the products of combustion and furnace gases will first impinge against the lower portion of the boiler shell 10 nearest the combustion chambers 20 and 22 and then turn back within the chamber 17 and pass through the different groups or banks A, B and C of fire tubes 26, 26, within the boiler shell 10 and thence into the smoke box 26 and finally out of the opening 27 to the stack.

As the heat of the hot gases is imparted to the water within the boiler shell 10, said water adjacent to the lower section of the boiler shell and fire tubes becomes lighter or lower in specific gravity and tends to rise and passes upwardly in the vertical passageways 29, 29 between the boiler shell and outer fire tubes 26, and also up the plurality of vertical passageways between the fire tubes 26, 26 of the groups or banks A, B and C, as shown by the arrows in Fig. 2. This action of the ascending water with the entrained globules of steam causes the body of water at the upper and center section of each of the groups A, B and C, of tubes, to assume a higher level than the water adjacent to the vertical passageway, 28, 28, between the groups of tubes, and hence this elevated water necessarily flows toward and downward the nearest unrestricted passageway 28, and hence immediately removes this lifted water from the entire upper section of the boiler for the efficient release of the steam and prevent priming by the rising steam not being able to entrain water in passing to the steam dome. The water of greater specific gravity at the upper section of the boiler sinks and passes down the vertical passageways 28, 28, between the groups or banks A, B and C, and replaces the heated water having passed up from the lower section of the boiler as above described.

This circulation of the water upwardly between the tube 26 and between the tubes and boiler shell and downwardly in the passageways 28, 28, between the groups or banks A, B and C of the tubes, as indicated by the arrows in Fig. 2, continues throughout its length and each transverse section of the boiler and finally the water within the boiler becomes heated to such a degree that globules of steam are formed which rise with the ascending column of water, and on reaching the upper surface of the water are liberated from the water and accumulate in the upper section or steam space of the boiler and will be withdrawn therefrom to be used as the occasion requires in the plant.

From the foregoing disclosure of construc-

tion and operation of the invention, it will be seen that I have devised a boiler of return tubular type, in which the circulation is at all times positive and in a well defined circulatory path or as termed by me in a "uniflow" direction, and all the water at the sides, interior, and extreme bottom and at every section of the boiler is kept in constant and rapid circulation.

10 In providing a boiler of the arrangement and grouping of fire tubes as shown in the present invention, the water circulates downwardly in two well defined paths, one on each side of a vertical plane passing through 15 the center of the boiler, and upwardly in two distinct paths adjacent to and around the shell, these downwardly and upwardly moving paths of water insuring at all times and under all conditions of working the 20 boiler and temperatures of the furnace, a positive and well defined circulation without the aid of mechanical devices, ejectors, deflectors, or similar expedients.

Also the arrangement and grouping of 25 fire tubes causes the proper and active circulation of the water in all planes at right angles to the longitudinal center line of the boiler, and the rapidity or speed of said circulation at different transverse sections along 30 the length or axis of the boiler is in direct proportion to the heat of the furnace gases impinging against the boiler at each particular transverse section, and the circulation of each section is independent of that 35 of any other section, thereby insuring a most efficient operation and steaming of the boiler.

From the arrangement, size of and grouping of the fire tubes a maximum amount of 40 heating surface is obtained and averaging fifty per cent. more than is usually obtained in a boiler of the same diameter and length made according to the old constructions.

By providing the proper circulation and 45 arranging the size and number of fire tubes as in the present invention, there is obtained a rapid moving thin film of water within the boiler adjacent to a large heating surface formed by the many fire tubes, and at 50 the same time there is created a sufficient cross-section tube area, which enables the maximum volume and temperature of heated gases to pass through the tubes at the best velocity to efficiently and quickly convey the heat of said gases to the water arranged to the best advantages and plurality of films in said boiler to receive said heat, 55 thereby greatly increasing the heat transmission efficiency from the furnace gases to the water.

From the foregoing disclosure as to construction, mode of operation and advantages of my invention, it will be readily seen that all the objects recited in my statement of 65 invention are fully carried out, and while

I have described and shown my preferred form of invention, I do not limit myself to these specific forms, as many changes and modifications will readily suggest themselves to anyone skilled in the art, as, for example, instead of three groups or banks of fire tubes, as shown, four, five or any other number of groups or banks of fire tubes could be equally well employed, where it is desired to obtain greater horsepower or volume of steam, without departing from the spirit of my invention.

What I claim is:

1. A return flue boiler comprising a shell, a plurality of separated groups or banks of horizontal fire tubes arranged within the shell from the upper section of the boiler down to the lower section of the boiler shell and the outer tubes of the outer groups being spaced from the boiler shell, thereby forming unobstructed narrow longitudinal vertical passageways between the groups or banks of fire tubes and passageways between the outer tubes and the boiler shell, said vertical passageways between the groups of tubes being arranged intermediate of the central vertical plane and the outer shell of the boiler, whereby when heat is applied to the exterior of the lower portion of the shell and to the interior of the fire tubes, the water within the boiler shell elevated at the upper and central section of each group of fire tubes during the generation of steam within the boiler, is permitted to directly pass into and circulate in a downward direction in the vertical passageways between the groups or banks of fire tubes to the bottom section of the boiler and thence in an upward direction between the rows of fire tubes in each group or bank and in the passageways between the boiler shell and the outer rows of fire tubes of the outer groups or banks and the generated steam will pass unobstructedly into the upper steam space of the boiler.

2. A return flue boiler comprising a shell, means for heating the underside of the shell, a plurality of separated groups or banks of horizontal fire tubes arranged within the shell from the upper section of the boiler down to the lower section of the boiler shell and the outer tubes of the outer groups being spaced from the boiler shell, thereby forming unobstructed narrow longitudinal vertical passageways between the groups or banks of fire tubes, and passageways between the outer tubes and the boiler shell, said vertical passageways between the groups of tubes being arranged intermediate of the central vertical plane and the outer shell of the boiler, whereby when heat is applied to the exterior of the lower portion of the shell and to the interior of the fire tubes, the water within the boiler shell elevated at the upper and central section of

each group of fire tubes during the generation of steam within the boiler, is permitted to directly pass into and circulate in a downward direction in the vertical passageways between the groups or banks of fire tubes to the bottom section of the boiler and thence in an upward direction between the rows of fire tubes in each group or bank and in the passageways between the boiler shell and the outer rows of fire tubes of the outer groups or banks and the generated steam will pass unobstructedly into the upper steam space of the boiler.

3. A return flue boiler comprising a shell, a plurality of separated groups or banks of horizontal fire tubes arranged within the shell from the upper section of the boiler down to the lower section of the boiler shell and the outer tubes of the outer groups being spaced from the boiler shell, thereby forming unobstructed narrow longitudinal vertical passageways between the groups or banks of fire tubes and passageways between the outer tubes and the boiler shell, said vertical passageways between the groups of tubes being arranged intermediate of the central vertical plane and the outer shell of the boiler, vertical circulating funnels disposed in said passageways between the groups or banks of fire tubes, whereby when heat is applied to the exterior of the lower portion of the shell and to the interior of the fire tubes, the water within the boiler shell elevated at the upper and central section of each group of fire tubes during the generation of steam within the boiler, is permitted to directly pass into and circulate in a downward direction through the vertical circulating funnels between the groups or banks of fire tubes to the bottom section of the boiler and thence in an upward direction between the rows of fire tubes in each group or bank and in the passageways between the boiler shell and the outer rows of fire tubes of the outer groups or banks, and the generated steam will pass unobstructedly into the upper steam space of the boiler.

4. A return flue boiler comprising a shell, a plurality of separated groups or banks of horizontal fire tubes arranged within the shell from the upper section of the boiler down to the lower section of the boiler shell and the outer tubes of the outer groups being spaced from the boiler shell, thereby forming unobstructed narrow longitudinal vertical passageways between the groups or banks of fire tubes and passageways between the outer tubes and the boiler shell, said vertical passageways between the groups of tubes being arranged intermediate of the central vertical plane and the outer shell of the boiler, and the fire tubes of each group disposed in straight vertical rows and staggered horizontal rows and ar-

ranged to form unobstructed straight vertical passageways between said tubes, whereby when heat is applied to the exterior of the lower portion of the shell and to the interior of the fire tubes the water within the boiler shell elevated at the upper and central section of each group of fire tubes during the generation of steam within the boiler, is permitted to directly pass into and circulate in a downward direction in the vertical passageways between the groups or banks of fire tubes to the bottom section of the boiler and thence in an upward direction between the rows of fire tubes in each group or bank and in the passageways between the boiler shell and the outer rows of fire tubes of the outer group or banks, and the generated steam will pass unobstructedly into the upper steam space of the boiler.

5. A return flue boiler comprising a shell, a plurality of separated groups or banks of horizontal fire tubes arranged within the shell from the upper section of the boiler down to the lower section of the boiler shell and the outer tubes of the outer groups being spaced from the boiler shell, thereby forming unobstructed narrow longitudinal vertical passageways between the groups or banks of fire tubes and passageways between the outer tubes and the boiler shell, said vertical passageways between the groups of tubes being arranged intermediate of the central vertical plane and the outer shell of the boiler, and the two upper horizontal rows of fire tubes being disposed in staggered relation and arranged to form unobstructed straight vertical passageways between said tubes, whereby when heat is applied to the exterior of the lower portion of the shell and to the interior of the fire tubes, the water within the boiler shell elevated at the upper and central section of each group of fire tubes during the generation of steam within the boiler, is permitted to directly pass into and circulate in a downward direction in the vertical passageways between the groups or banks of fire tubes to the bottom section of the boiler and thence in an upward direction between the rows of fire tubes in each group or bank and in the passageways between the boiler shell and the outer rows of fire tubes of the outer group or banks, and the generated steam will readily escape through the spaces between the upper two rows of staggered fire tubes and the boiler shell, and unobstructedly pass into the upper steam space of the boiler.

6. A return flue boiler comprising a shell, three separated groups or banks of horizontal fire tubes arranged within the shell from the upper section of the boiler down to the lower section of the boiler shell and the outer tubes of the outer groups being spaced from the boiler shell, thereby forming unob-

structed narrow longitudinal vertical passageways between the outer tubes and the boiler shell, said vertical passageways between the groups of tubes being arranged intermediate of the central vertical plane and the outer shell of the boiler, whereby when heat is applied to the exterior of the lower portion of the shell and to the interior of the fire tubes, the water within the boiler shell 10 elevated at the upper and central section of each group of fire tubes during the generation of steam within the boiler, is permitted to directly pass into and circulate in a downward direction in the said vertical passageways between the groups or banks of fire tubes to the bottom section of the boiler and thence in an upward direction between the rows of fire tubes in each group or bank and in the outer passageways between the boiler shell and the outer rows of fire tubes of the outer groups or banks, and the generated steam will pass unobstructedly into the upper steam space of the boiler.

7. A return flue boiler comprising a shell, 25 means for heating the underside of the shell, separated central and two side groups or banks of horizontal fire tubes arranged within the shell from the upper section of the boiler down to the lower section of the boiler shell and the outer tubes of the two side

groups being spaced from the boiler shell, thereby forming two inner unobstructed narrow longitudinal vertical passageways between the central and two side groups or banks of fire tubes and a passageway between the outer tubes of each of the side groups and the boiler shell, said vertical passageways between the groups of tubes being arranged intermediate of the central vertical plane and the outer shell of the boiler, 35 whereby when heat is applied to the exterior of the lower portion of the shell and to the interior of the fire tubes, the water within the boiler shell elevated at the upper and central section of each group of fire tubes 40 during the generation of steam within the boiler, is permitted to directly pass into and circulate in a downward direction in the two inner vertical passageways between the central and two side groups or banks of fire tubes to the bottom section of the boiler and thence in an upward direction between the rows of fire tubes in each group or bank and in the passageways between the boiler shell and the outer rows of fire tubes of each of 50 the side groups or banks and the generated steam will pass unobstructedly into the upper steam space of the boiler.

In testimony whereof I affix my signature:
HOWARD J. WEBSTER.
